CLAIM

The ornamental design for a clipper for small diameter plastic rod, as shown and described.

DESCRIPTION

FIG. 1 is an upper front perspective view showing my new design for a clipper for small diameter plastic rod, the clipper shown in an open position;

FIG. 2 is an enlarged right side elevational view of the clipper in its closed position;

FIG. 3 is an enlarged front end view of the clipper in open position;

FIG. 4 is an enlarged right side elevational view of the clipper in its open position;

FIG. 5 is an enlarged left side elevational view of the clipper in its open position;

FIG. 6 is an enlarged rear end view of my clipper in its open position;

FIG. 7 is an enlarged top plan view of the clipper; and,

FIG. 8 is an enlarged bottom plan view of the clipper.
